UNITED STATES PATENT OFFICE.

EDWARD F. HAMILL, OF CHICAGO, ILLINOIS.

DESIGN FOR A COMBINED SIGNAL AND OUTLET BOX FOR ELECTRICAL CONDUCTORS.

53,905.

Specification for Design.

Patented Oct. 7, 1919.

Application filed May 22, 1919. Serial No. 299,026. Term of patent 7 years.

To all whom it may concern:

Be it known that I, EDWARD F. HAMILL, a citizen of the United States, residing at Chicago, in the county of Cook and State of Illinois, have invented a new, original, and ornamental Design for a Combined Signal and Outlet Box for Electrical Conductors, of which the following is a specification, reference being had to the accompanying drawing, forming part thereof.

Figure 1 is a front elevation, and
Fig. 2 is a side elevation.

I claim:

The ornamental design for a combined signal and outlet box for electrical conductors, substantially as shown.

EDWARD F. HAMILL.
